UNITED STATES PATENT OFFICE.

JOHN ALBERT CHAPPUIS, OF LA CHAUX-DE-FONDS, SWITZERLAND.

ALARM.

1,341,298.

Specification of Letters Patent. Patented May 25, 1920.

Application filed November 20, 1919. Serial No. 339,377.

To all whom it may concern:

Be it known that I, JOHN ALBERT CHAPPUIS, a citizen of the Swiss Confederation, and resident of La Chaux-de-Fonds, Switzerland, have invented a certain new and useful Improvement in Alarms, of which the following is a specification.

The subject of the present invention is an alarm clock in which the movement is 10 closed in a casing the base of which is formed by the bell of the alarm which is fixed to the movement. The feature of the invention is that the bell is formed at its central portion with a recess within which 15 are located the winders and hand setters.

This arrangement permits of suspending the alarm from a wall as the winders and setters need not project beyond the rear edge of the alarm casing. The bell comprises 20 preferably an outer rim connected to the central part by a flange in such manner that the sounding zone of the bell consists only of the said rim. As a result the elements 25 for attachment of the bell, viz. screws, nuts, etc., may be located in any position on the central part of the latter without prejudicial effect on the sound or tone of the bell.

One embodiment of the invention is illustrated in the accompanying drawing in 30 which, Figure 1 is a rear view of the alarm, while Fig. 2 is a section on the line A—B of Fig. 1, those parts not necessary for an understanding of the invention being omitted.

In accordance with the embodiment shown, 35 the movement of the alarm is mounted in a frame comprising two plates *a*, *b*, assembled by pillars *c* by means of nuts *c'*. Most of the parts of the movement are not shown, but the arbors *d* and *e* of the two winding 40 barrels as well as the two staffs *f*, *g*, each of which is provided with a crown *f'* or *g'* are shown. By operation of these crowns the staffs *f* and *g* may be turned and the hour and minute and alarm hands thus set. 45 The barrel arbors *d*, *e*, each are fitted with

a winder *h*, *i*. The alarm movement is enclosed in a casing *k* the base of which is formed by a bell *m* which is fixed to the plate *b* and spaced therefrom by three nuts *n*. The central part of this bell is formed 50 with a recess *m'* connected to the outer rim *o* of the bell by a flange *m''*. In the recess *m'* are disposed the winders *h*, *i*, and the crowns *f'*, *g'*, which pass freely through openings formed in the bell. In consequence the alarm may be hung on a wall without the winders and crowns touching the latter. The sounding part of the bell consists only of the rim *o*, the flange *m''* forming a neutral zone and preventing the 60 central part *m'* from participating in the sound vibrations of the rim. The nuts *n* which secure the bell may thus be placed in any position on the central part *m'* even quite near the edge, as shown in the drawing, without the sound and tone of the bell 65 being affected.

What I claim is:

1. An alarm clock comprising a casing and a bell mounted at the base or back of and 70 within said casing, said bell being recessed centrally so as to afford a housing or receptacle, within the rear edge of said casing, for the winders and other parts.

2. An alarm clock comprising a casing 75 and a bell, mounted at the base or back of and within said casing, said bell being recessed centrally so as to afford a housing or receptacle, within the rear edge of said casing, for the winders and other parts, said 80 bell comprising, outside of its central recess, a flange and an exterior or peripheral sounding rim.

In testimony whereof I have signed my name to this specification in the presence of 85 two subscribing witnesses.

JOHN ALBERT CHAPPUIS.
